UNITED STATES PATENT OFFICE.

GIUSEPPE FURMANIK, OF ROME, ITALY, ASSIGNOR TO GIACOMO ACHILLE CALABI, OF ROME, ITALY.

PARACHUTE.

Application filed October 18, 1926, Serial No. 142,488, and in Italy June 16, 1926.

This invention regards improvements in parachutes and particularly the attachment of the user to the vertex of the rope system and the devices for breaking or cutting, at 5 the moment of the leap, the cord of the bag containing the parachute.

The invention is illustrated by way of example in the annexed drawings in which

Fig. 1 is a front view of the waist-belt of 10 the aircraft pilot, with its various attaching or hooking devices.

Fig. 2 a partially sectioned elevation of 15 these devices shown in their hooked position in full lines, and in their unhooked position in dotted lines,

Fig. 3 represents the devices for breaking or cutting the cord of the knapsack containing the parachute, and

Fig. 4 is a longitudinal section of the said 20 breaking or cutting devices.

In the said figures A and A' are the two parts of the waist-belt, solidly connected to the knapsack. At 1 on part A' two sprocket chains are fixed, passing in the interior of 25 two boxes 2 connected together by a bow 3. The covers 4 of said boxes 2 are hinged at 5 on the hindmost sides of the boxes. To the front part of covers 4, at 6, the buckle 7 is hinged.

The said covers in their interior have teeth 30 8 corresponding to the links of the sprocket chains. When the covers 4 are raised their teeth 8 are disengaged from the sprocket chains and the boxes 2 are free to slide on 35 the chains so that the clasping of the buckle 7 may be regulated according to the circumference of the waist of the bearer. On part A of the waist-belt the clasping and un-

clasping devices of buckle 7 are suitably fixed. 40 They consist of a part 9 rigidly fixed to the waist-belt, the raised sides 10 of which form the hooks of buckle 7, whilst the sides 11 form the sockets for the passage of the lock-bolts 12 slidable in a bearing or sheath at 13 to the fore end of the moveable part 14 hinged in turn, at 15, on the said rigid part 9. On the part 14 two levers 16 are pivoted which operate the lock-bolts 12 so as to disengage them from the sockets 11 in the act of un- 45 clasping. The levers 16 pass through holes provided in the bolts 12 so that when they are pressed toward one another in the direction of the arrows in Fig. 1 the bolts are withdrawn from the sockets 11. 17 is a reaction

spring controlling the movements of the lock- 55 bolts.

18 are elastic members which in position of closure keep the buckle 7 in place, and also covers 4 of boxes 2 are kept closed by said 60 members 19.

At the top of part A of the waist-belt a ring 20 for brace 21 of the knapsack is fixed, and at the bottom a ring 22 for the hook by which the pilot is fixed to his seat.

The devices for snapping or cutting the 65 line 23 of the bag or knapsack 24 enclosing the parachute comprise a tube 25 containing a piston 26 having a longitudinal slot 27 with sharpened edges, through which passes the cord 23. The piston 26 has a spring 28 70 for restoring it to its position. The end 29 of the piston is connected to a cord or Bowden line.

Two of the said devices are applied to 75 line 23, the one acting automatically at the moment of the leap, the cord 30 being attached to the waist belt, whilst the other, of the Bowden system, is operated by lever 31 at the will of the pilot.

Clasping and unclasping of waist-belt is 80 effected as follows:

After the pilot has donned the knapsack which is kept in place by brace 21 attached to ring 20 of part A of waist-belt, the buckle 7 is fastened according to circumference of 85 waist of bearer, causing the bow 3 and boxes 2 to slide on the sprocket chains, the covers 4 being raised. To the end of the said covers, at 6, the buckle 7 is hinged. On closing the covers 4 their rigid teeth 8 engage the links of the sprocket chains thereby effecting closure, whereupon buckle 7 is turned down so as to bend the elastic members 18 and placing itself under the latter so as to engage hooks 10 of fixed part 9 and effect a sure and solid connection of parts A and A' of waist-belt. 90 The pilot then attaches himself to his seat by means of ring 22.

In order to promptly disengage himself 100 from the parachute when landing he pulls, in the direction of the arrows, the two levers 16 pivoted to the moveable part 14, which cause the lock-bolts 12 to re-enter in 13 from their sockets 11 on the fixed part 9. By this first operation the moveable part 14 turning on its 105 hinges 15 is raised thereby releasing the buckle 7 from the hooks 10. The buckle being moveable and rotatably connected at 6 to

covers 4 raises the latter thereby disengaging the teeth 8 from the sprocket chains, with the result of the two parts A A' of the waist-belt being disengaged, Figs. 1 and 2. In the said figures the outermost free ends of the sprocket chains are omitted for the sake of clearness.

It is understood that all of the parts and subject matter of the present improvements may be modified according to circumstances 10 without departing from the spirit of the invention.

Having now particularly described and ascertained the nature of said invention and in what manner the same is to be performed 15 I declare that what I claim is:

In a parachute, a waist belt, chains connected at one end to the belt, boxes slideable relative to the chains, means connecting said

boxes, said boxes including each a hinged cover having teeth adapted for insertion in 20 the chain, a movable buckle connected to the free end of each cover, a plate connected with the other end of the waist belt, hooks associated with the last mentioned plate and engaging the buckles, the last mentioned plate being provided with lugs and being hinged to a movable plate provided with a 25 sheath, lock bolts in said sheath, spring means coacting with said lock bolts, said lock bolts engaging pipes provided on the last mentioned plate, and hinged lever arms running through holes provided in the lock bolts and operating in conjunction with the latter.

In testimony whereof I have hereunto signed my name.

GIUSEPPE FURMANIK.
